UNITED STATES PATENT OFFICE.

EMMET PLATTEN, OF GREEN BAY, WISCONSIN.

REFRIGERATING APPARATUS.

Application filed May 16, 1927. Serial No. 191,718.

This invention relates to refrigerating apparatus and is particularly directed to household refrigerating apparatus.

Objects of this invention are to provide a novel refrigerating apparatus in which a plurality of compartments are arranged in a row and provided with a metal floor and preferably with metal side walls intimately connected with the metal floor so as to provide a refrigerating unit that will conduct the heat through the floor and from the side walls, which heat is conducted from the foods or material placed in the individual compartments.

Further object is to provide a novel form of refrigerating unit suitable for apartments and adapted to be located in a place freely accessible to all of the tenants and to be constructed so that each tenant is provided with a separate compartment free from those of all the other tenants so that the food contained in one compartment will not contaminate the food in the other compartments, and to provide a single refrigerating unit in actual physical contact with the metal linings of the different compartments.

Further object is to provide a novel means for yieldingly holding the pipes of the refrigerating unit in intimate engagement with the metal floor so that a direct conduction from the rest of the metal of the compartment of the refrigerating unit is obtained.

Further objects are to provide a novel form of refrigerating apparatus having the characteristics noted above in which metal lining is provided with a metal spring sealing type of gasket, and which is provided with a door to effect a conducting contact for the walls of this compartment when the door is closed.

Embodiments of the invention are shown in the accompanying drawings, in which:

Figure 1 is a front view of the apparatus with a portion broken away.

Figure 2 is a transverse sectional view of the line 2-2 of Figure 1.

Figure 3 is a transverse sectional view of a modified form showing a novel means of holding the refrigerating unit in contact with the metal floor.

Referring to the drawings it will be seen that the pair of compartments 1 and 2 has been shown to illustrate the invention, although it is to be distinctly understood that any number of compartments may be employed or arranged in the device. The com-

partments are each lined along four vertical walls with a metal lining 3 which is intimately joined to the metal floor 4.

The refrigerating unit may be of any of the conventional types, such as, that known commonly as "Frigidaire" and comprising a drum 5 which is provided with pipes 6, extending outwardly from the cabinet. The unit also comprises upper and lower stretches of pipes 7 and 8 joined to the drum 5.

As shown in Figures 1 and 2, it is to be noted that the upper stretches 7 of the pipes are held yieldingly against the floor by the metal plate 9. The plate is provided with bellows like or pleated metal strips 10 at its edges through which the attaching bolts 11 extend.

It is to be noted further that the side walls continue downwardly and from lower compartment 12. These compartments are lined throughout with metal as indicated by reference character 13, and a sealed trap 14 is provided for this compartment.

The compartments are surrounded by a thermal insulating sheet or packing 15. This insulating material extends around the lower compartment 12 and each wall of the individual refrigerating compartments. Each of the refrigerating compartments is provided with a door 17 provided with a latch or key lock 18. The doors 17 for the individual compartments are also provided with a lining or packing 19 of insulating material as may be seen from figure 2. Preferably also their inner sides are provided with a metal lining 20.

It is to be noted that each door, when in closed position, is sealed with rubber gasket 21 which extends completely around door opening and is suitably held in place.

Further it is to be noted that a spring metal contact bellows like strip 22 extends around the vertical and bottom ends of the doors and is soldered or held secure to the metal lining of the compartment.

It is to be noted further that each compartment is provided with metal shelves 23 which are rigidly attached to the vertical metal lining.

Preferably, the cabinet is provided with plurality drawers 24 which project outwardly from the face of the cabinet and in which cubes of ice are adapted to be frozen in the usual manner. These drawers are preferably positioned between the upper and lower

stretch of the pipes 7 and 8 of the refrigerating unit.

A modified form of construction for holding the refrigerating unit in contact with the floor of the compartment is shown in Figure 3 from which it will be seen that the floor indicated by reference character 25 is preferably provided with longitudinally extending reenforcing metal strip 26 so that the 10 floor as well as the lining may be made of thinner metal. These reenforcing strips receive the end of the attaching bolts 27 which pass through the bottom metal plate 28. This metal plate encloses both the upper and lower 15 stretch of pipe 7 and 8. The bolts 27 also pass through the corrugated or fluted metal sealing strips 29.

It is to be noted particularly that the refrigerating unit may be quickly removed for 20 repairing without requiring any soldering or heating.

It will be seen also that the novel form of refrigerating apparatus has been disclosed by this invention which is suitable for use in 25 apartment houses to provide each of the tenants with an individual compartment maintained at a low temperature.

From actual experiments conducted with this apparatus it has been found that a very 30 small amount of energy is required to run the apparatus at the desired low temperature.

It is to be particularly noted that although a single refrigerating unit or a battery of such unit is used for simultaneously refrigerating 35 all of the compartments that, nevertheless, each compartment is distinct and separate from all other compartments.

It will be seen further that a novel method of refrigerating for each individual compartment has been provided by this invention and 40 that the heat from the food placed in the compartments conducts by contact to the side walls and floors of the compartments and that these metal walls and floors conduct the 45 heat to the refrigerating unit which carries it away.

As a single unit for household or domestic use, it consumes much less power, it requires

a much smaller, less expensive motor, and can be sold to the consumer for much less than 50 any other type of refrigerator, and due to the direct conduction, cost of operation is greatly reduced.

It is very compact, because no space has to 55 be allowed for circulating air.

Although the invention has been described in considerable detail, such description is intended as illustrative rather than limiting as the invention may be variously embodied and as the scope of such invention is to be determined as claimed.

I claim:

1. A refrigerating apparatus having one or more food compartments each having metal walls, and the floor composed of a tank 65 into which the refrigerant is expanded directly, materials to be cooled being placed in contact with the floor or walls, the heat being removed by direct conduction and carried to the refrigerating unit, a metallic lined door and a yielding metallic connection between the door and juxtaposed walls forming an uninterrupted heat conducting contact between the door and the metallic lining of the refrigerator cabinet. 70

2. A refrigerating apparatus having one or more food compartments each having metal walls, a metal lined door and a yieldable metallic connection between the door and juxtaposed walls forming an uninterrupted 80 heat conducting contact between the door and the metal walls of the compartments.

3. A refrigerating apparatus having one or more food compartments each having metal walls, a metal lined door and a yieldable metallic elongated strip forming connection between the door and juxtaposed walls of the compartments, forming an uninterrupted heat conducting contact between the door and the metal lining of the refrigerating 85 cabinet. 90

In testimony that I claim the foregoing I have hereunto set my hand at Green Bay, in the county of Brown and State of Wisconsin,

EMMET PLATTEN.
